**PIN ORIENTING MEANS FOR VIBRATORY
BOWL FEEDERS**

William H. Atkinson, San Mateo, Calif., assignor to
Maromatic Company, Inc., Burlingame, Calif., a cor-
poration of California

Filed Sept. 14, 1964, Ser. No. 396,177
3 Claims. (Cl. 198—33)

My present invention relates to tumbler locks and more particularly to a means for orienting the key bit engaging pins carried by the plug of such locks as an initial step in the assembly.

An object of the invention is to provide a tumbler pin orienting device of the vibratory feeder type by which the bit engaging pins of segregated sizes may be properly oriented for insertion into the plug of a tumbler lock during assembly.

Another object of the invention is to provide an orienting means for a vibratory feeder of the "Syntron" and "Minimus" types having a track of novel configuration that will orient tumbler pins to be fed therefrom with their rounded bit engaging ends forward and reject prior to delivery from the feeder any such pins not so properly oriented.

Other objects and advantages will be in part evident to those skilled in the art and in part pointed out hereinafter in connection with the accompanying drawing wherein there is shown by way of illustration and not of limitation a preferred embodiment of the invention.

In the drawing wherein like numerals refer to like parts:

FIGURE 1 is a perspective view of a "Minimus" vibrating feeder of conventional form,

FIGURE 2 is an enlarged view of a portion of the track of such a feeder showing a detail of construction,

FIGURE 3 is a fragmentary top view showing the manner in which improperly oriented key bit engaging pins will be dropped from the line at a rejection point when the feeder is in operation, and,

FIGURE 4 is a view showing the manner in which properly oriented tumbler pins will by-pass the rejection point of the track.

FIGURE 5 is a fragmentary top view looking down on a modified form of the invention, and

FIGURE 6 is a fragmentary perspective view showing a side elevation of the arrangement of FIGURE 5.

Before considering the various types of orienting devices that can be added to a vibratory feeder bowl, it is well to have a conception of the manner in which parts travel up the inclined spiral track of a bowl. Visualize a single part on a bowl track as the coil of the electromagnet is energized by a pulse. When this occurs, the armature, bowl, and bowl mounting plate are pulled abruptly down and away from the part by the force of the magnet. Because of the angular leaf-spring arrangement, a radial twist is imposed on the downward movement, distorting the springs.

When the bowl is thus pulled downward, the part drops to a new spot on the track which is in advance of its original position and when the coil is de-energized, the springs will return the bowl to its original position. While the vertical motion of the part is not visible because of the high-frequency movement which seems to make the part flow up the track, an average speed of 20 f.p.m. is possible.

The first step is orienting a part is to evaluate it in terms of its natural feeding characteristics and the requirements of the application. What, if any, is its predominant attitude? How many attitudes does it assume? What is the desired attitude, or is there free choice in this respect?

2

Chief problem in tooling a vibratory feeder bowl is that the user usually expects too much to happen to a part before it is delivered to the discharge point of the bowl. He often neglects to realize that some final positioning and orientation can be accomplished better and more economically by properly designed out-of-bowl tracks and escapement devices. Quite frequently, the user requires that individual parts arrive at the end of the in-bowl track in exactly the position and attitude in which his machine or process will accept them.

To determine how many attitudes a part will take and to find out if any one attitude is predominant, the parts are put in a bowl and their travel up the track is examined. Precise oriented feeding of small parts and products has always presented problems to manufacturing engineers. Through the years, various methods have been employed to feed parts, such as rotating ring selectors, oscillating boxes and blades, rotating barrels and drums, elevating selectors, magnets on conveyor belts, paddle-wheel hoppers, and vibratory hoppers and conveyors. Each method has its own advantages and disadvantages. However, for automatically feeding and orienting small parts of all types and configurations, the vibratory bowl feeder remains one of the most frequently used devices.

With full knowledge of the above advantages and disadvantages of the so-called vibratory bowl feeders and after a thorough research in this field it has been discovered that there is no bowl type feeder having the capability of orienting tumbler pins such as are now employed in tumbler locks within the bowl and without recourse to an external orienting means. Therefore the novelty and advantage of my invention as will be hereinafter pointed out resides in the fact that the pins of different lengths may be oriented to their proper attitude within the bowl for discharge therefrom and directly to a point of use without recourse to any external orienting means or device. It may therefore be stated that the primary object of my invention is to provide a track configuration for a vibratory pin feeding bowl by which a feeding of segregated pins of uniform length to a pin loading station for final insertion into the lock plug, either by hand or other means.

The nearest approach to a solution of the problem here presented consists of a vibratory bowl of conventional form in which means is provided along the track of the bowl that will stand the pins vertically on end against the outer wall of the track with their rounded ends uppermost and finally allowing these pins to drop through an accommodating opening in the bottom of the track at the discharge end thereof. This solution, however, will require an external pin orienting means for it is necessary that the rounded end of these pins when inserted into the plug of a lock be lowermost for engagement with the bits of a key. A further difficulty with this particular solution resides in the fact that some key bit engaging pins of a tumbler lock are slightly rounded at the other end and in many cases they are provided with a slight chamfer at the blunt end which would preclude, or at least make difficult, an upright orientation of the pins in the track with the key bit engaging end uppermost.

As distinguished from the above solution I have by my invention provided a vibratory feeder bowl track which will deliver the pins in a proper attitude for direct delivery from the bowl for automatic insertion into the plug of a lock without recourse to any external oriented means.

For a better understanding of the invention reference is now made to the accompanying drawing where in FIGURE 1 there is shown a vibratory bowl type feeder of

the so-called "Minimus" type having a bowl 10 that is formed of cast aluminum, Teflon or hard setting plastic material of light construction having a bottom 11 with a progressively inclined spiral track 12 extending from the bottom 11 to a point of discharge 13 at the upper end of the track 12. In this showing the point of discharge 13 of the bowl 10 is continued through a spring 14 having tightly wound convolutions which provides a tubular conduit for directing the pins from the bowl 10 to a point of use. The bowl 10 has a magnetic armature secured to its bottom that is supported in spaced relation with the core of an electromagnet within a housing 15 by inclined resilient supporting members or struts 16 that are carried by a base 17 having sufficient mass or which is adapted and arranged to be secured upon a firm stationary supporting means. The electromagnet within the housing 15 is energized by a suitable source of alternating current power through conductors 18.

As is illustrated in more detail in FIGURE 2 of the drawing the track 12 of the bowl 10 is at one or more points along its length provided with a shoulder 19 that is formed by a recess 20 in the vertical wall thereof against which the blunt end of an improperly oriented pin 21 will abut as here shown by dot-dash lines, whereas when properly oriented the pin designated by the numeral 22, with its rounded end leading will pass over the shoulder 19. When the improperly oriented pin 21 is thus stopped the following properly oriented pin 22 will operate to crowd the pin 21 from the track 12 and cause it to return to the bottom 11 of the bowl.

The above operation is well illustrated in FIGURES 3 and 4 where in FIGURE 3 the improperly oriented pin 21 is shown as retarded in its progress along the track 12 by the shoulder 19 in such manner that the following properly oriented pin 22 will operate to crowd the pin 21 from the track 12 for a return to the bottom 11 of the bowl 10. As the pins move along the track 12 with the bowl 10 rotating in the direction indicated by arrows, all of the properly oriented pins will continue in their travel past the shoulder 19 without interruption.

In FIGURES 5 and 6 there is shown a modified form of the invention in which the shoulder 19 described above is formed by a vertically disposed pin 23 that is located in bisecting relation with the outer wall 24 of the pin track 12. The pin 23 is here shown as milled or cut substantially in half lengthwise to form a vertical surface 25 in the surface of the wall 24 which when rotated clockwise as here indicated will expose a portion of the outer wall 24 of the track 12. This will present a shoulder forming surface 26 as a portion of the drilled hole into which the vertical pin 23 is positioned. At the lower end of the surface 25 and flush with the pin track 12 the complete diameter of the pin 23 will be exposed as at 27 and thus complete the surface of the track 12. With this arrangement it will be seen that by rotating the pin 23 the depth or width of the shoulder forming surface 26 may be varied as required to accommodate tumbler pins of the different lengths. In this respect it will be noted that the surface 25 of the pin 23 is shown in FIGURE 5 as slightly off-center with

center of the pin 23 located substantially in line with the surface of the outer wall. As an alternative if the surface 25 of the pin 23 is located directly on center the pin approached side of the pin 23 may be relied upon to function in a manner similar to that of the pin orienting shoulder 26.

While I have for the sake of clearness and in order to disclose the invention so that the same can be readily understood, described and illustrated a specific device and arrangement, I desire to have it understood that this invention is not limited to the specific means disclosed, but may be embodied in other ways that will suggest themselves to persons skilled in the art. It is believed that this invention is new and all such changes as come within the scope of the appended claims are to be considered as part of this invention.

Having thus described my invention, what I claim and desire to secure by Letters Patent is:

1. In a vibratory bowl feeder having a spiral pin guiding track for delivering properly oriented tumbler pins to a lock plug assembly station having an outer wall with an obstruction by which improperly oriented pins will be stopped in their movement along said track, and characterized by the fact that said obstruction of the outer wall of the pin guiding track is formed by an increasing recession travelwise in the outer wall of the track.
2. In a vibratory bowl feeder having a spiral pin guiding track for delivering properly oriented tumbler pins to a lock plug assembly station having an outer wall with an obstruction by which improperly oriented pins will be stopped in their movement along said track, and further characterized by the fact that the obstruction in the outer wall of the pin guiding track consists of a vertical pin extending upwardly from the bottom of the track and standing adjacent to the vertical wall of the track.
3. In a vibratory bowl feeder having a spiral pin guiding track for delivering properly oriented tumbler pins to a lock plug assembly station having an outer wall with an obstruction by which improperly oriented pins will be stopped in their movement along said track, and further characterized by the fact that the obstruction in the outer wall of the pin guiding track comprises a rotatable pin extending vertically from the bottom of the track and in line with the receding outer wall of the track and having a flat surface extending substantially flush with the outer wall of the pin track, whereby the effect of said abutment may be adjusted to accommodate pins of different lengths.
